United States Patent Office.

RUDOLPH L. WALTER, OF WASHINGTON, DISTRICT OF COLUMBIA.

Letters Patent No. 104,382, dated June 14, 1870; antedated June 4, 1870.

IMPROVEMENT IN PAPER OR PAPER-AND-CLOTH NECK-TIES.

The Schedule referred to in these Letters Patent and making part of the same.

I, RUDOLPH L. WALTER, of Washington, in the District of Columbia, have invented certain Improvements in Neck-Ties, of which the following is a specification.

Nature and Objects of the Invention.

The nature and objects of my invention are to furnish to the public an economical neck-tie, made of cheap material, and more simple in construction than has hitherto obtained in the manufacture of said article, and it may be composed of printed paper, or of printed cloth and paper.

Description of the Accompanying Drawings.

Figure 1 is a plan, embodying my invention.

Figure 2 is a plan, embodying a modification of the same.

Figure 3 is a front view of the same.

Figure 4 is a vertical section of fig. 1.

Figures 5, 6, and 7, are plans of detached parts.

A is the body of my neck-tie, which may be cut out in a single piece, as shown in fig. 1, or composed of distinct pieces, as shown in fig. 2. It may be printed on its face, and the band C on its back, so that, when folded in position, the same figure or pattern will be presented to view, or the paper may be printed on both sides with the same figure, so that, when folded, the same figure will be presented to view, or the printing may be applied to both sides in different colors, as stated above.

C is the band, which folds around the middle of the neck-tie repeatedly. Said band may be colored or printed alike on both sides, or said color or print may be varied on either side thereof, and it may also differ in print or color with the body of the neck-tie.

d is the button-hole of the band aforesaid, and

f represents linen for protecting or strengthening the button-hole when the band is made of paper only. e, in fig. 2, is an eyelet for attaching the band C and the parts A and B together.

S S represent the bows of the device, and the points immediately above said bows serve to retain the neck-tie in an immovable or steadfast position.

In figs. 2, 5, and 6, the letters A and B are designed to represent the parts of the neck-tie which project from beneath the collar.

In attaching the neck-tie it is first buttoned at the band to the shirt-button, and then, by turning over the body of the device, the band is repeatedly folded around the middle of the neck-tie, which causes it to assume the appearance of the ordinary neck-tie, as shown in fig. 3.

I am aware that it is not new to cover paper foundations for neck-ties with a textile fabric, and also that neck-ties have been made reversible by patterns formed on both sides, and by covering both sides of the same with fabrics, and that the parts forming a tie have been attached together by a metal clasp, which also secure a band, which folds over to form the central band, and, being provided with a button-hole, the means for attachment to the collar-button.

Claim.

As a new article of manufacture, an imitation neck-tie, formed of a single piece, and consisting of the body A and folding-band C, provided with a button-hole for attachment to the collar-button, as shown and described.

RUDOLPH L. WALTER.
